UNITED STATES PATENT OFFICE.

HANNIBAL W. RAPPLEYE, OF PHILADELPHIA, PENNSYLVANIA.

REGULATOR FOR GAS-BURNERS.

SPECIFICATION forming part of Letters Patent No. 369,960, dated September 13, 1887.

Application filed April 7, 1887. Serial No. 233,969. (No model.)

To all whom it may concern:

Be it known that I, HANNIBAL W. RAPPLEYE, a citizen of the United States, and a resident of Philadelphia, Pennsylvania, have 5 invented certain Improvements in Regulators for Gas-Burners, of which the following is a specification.

The object of my invention is to so construct an automatic pressure-regulator for gas-burners and like purposes as to facilitate the fitting together of the parts, to provide for readily governing the action of the device, and to restrict the opening movement of the valve. This object I attain in the manner which I 15 will now proceed to describe, reference being had to the accompanying drawings, in which—

Figure 1 is a perspective view of a pressure-regulator constructed in accordance with my invention. Fig. 2 is an enlarged sectional 20 view of the same, and Fig. 3 is a perspective view of part of the device.

The frame of the regulator consists of an upper inlet branch, A, a lower outlet branch, B, and two hollow arms, *a* and *b*, the whole 25 forming an open frame, in which is contained the casing of the regulator, the latter comprising a lower shell, *d*, and an upper shell, *d'*, between which is confined a diaphragm, *f*, preferably of cloth so prepared as to be impervious to gas and proof against deterioration 30 thereby, although a diaphragm of metal or other available material may be used instead of the cloth, if desired. The lower shell of the regulator-casing has a hollow projection, 35 *g*, seated in a socket, *g'*, on the outer frame, suitable packing being interposed to prevent leakage at this point, and the upper shell has a threaded stem, *h*, to which is adapted a nut, *h'*, having a conical upper end seated in a 40 socket in the upper portion of the outer frame, so that by turning said nut the casing of the regulator may be elevated or depressed, it being understood that the casing is not free to turn. By reason of the conical end of the nut 45 bearing at the point on the frame, friction is reduced, and the nut is permitted to swing to some extent laterally to accommodate itself to any want of truth in the alignment of the regulator-casing. The inlet branch A of the 50 frame communicates, through a passage, *a'*, in the arm *a* of said frame, with the chamber beneath the diaphragm *f* of the regulator, the

gas in its flow passing through an opening, *i*, to which is adapted a conical valve, *m*, having a stem, *m'*, connected to the diaphragm *f*. The 55 arm *b* of the frame has a passage, *b'*, which communicates with the discharge branch B of the frame, and across the upper end of said passage extends a tubular plug, *D*, the bore *n* of which communicates with the chamber 60 beneath the diaphragm *f* of the regulator, and also through ports *n'* with the passage *b'* in the arm *b* of the frame.

The plug *D* is threaded externally for adaptation to threaded openings in the arm *b*, and 65 said plug should be notched, squared, or otherwise constructed at the outer end for the reception of a suitable implement whereby it may be turned, the inner end of the plug being reduced in diameter and fitted to a bushing, *p*, which is adapted to an opening in the lower shell, *d*, of the regulator-casing, suitable packing being used between the bushing and shell and between the bushing and plug, if desired. 75

Above the diaphragm *f* of the regulator is a cup or receptacle, *s*, which, in the present instance, is confined to the diaphragm by a thumb-nut, *s'*, adapted to the threaded upper end of the valve-stem *m'*, the latter having 80 beneath the diaphragm a flange or collar, *v*.

The cup *s* contains a number of pellets of lead or other suitable weights, whereby the action of the regulator is governed, the weighting of the cup being dependent upon the pressure desired at the burner or other outlet. 85 When this pressure is normal, the valve *m* occupies such a position as to permit a flow of gas sufficient to maintain the proper supply; but should the demand be such as to decrease 90 the pressure at the outlet the weight above the diaphragm *f* overcomes the pressure beneath the same, and said diaphragm is depressed so as to open the valve to a greater extent and permit a freer flow of gas to restore the normal pressure at the outlet, while if, on the other hand, the pressure at the outlet exceeds the normal pressure, the diaphragm *f* will be raised and the valve *m* caused to restrict the flow of gas to the lower chamber of 95 the regulator, so as to properly reduce the pressure at the outlet. 100

The upper shell, *d'*, of the regulator casing has an opening, *t*, to provide for the introduc-

tion of the weights into the receptacle *s* in setting the regulator, and so as to permit a free flow of air into and from the space above the diaphragm *f* as the latter falls and rises. In 5 order to prevent such a drop of the valve *m* as would cause the straining of the diaphragm *f* when gas is cut off from the regulator-chamber or the pressure therein is very much reduced, I place beneath said valve a transverse stem, 10 *w*, a portion, *w'*, of which is recessed or made eccentric, as shown, so that by partially turning the stem the downward movement of the valve may be restricted to any desired extent.

It will be evident that by the use of the nut 15 *h'* and plug *D* the parts can be readily fitted together or taken apart, and the ready inspection of any part of the regulator is permitted.

A laterally-projecting neck secured to the regulator-casing and adapted to but removable 20 from an opening in the discharge-arm of the frame may, if desired, replace the movable plug; but the use of the latter is preferred.

I claim as my invention—

1. The combination of the outer frame, having 25 hollow arms forming gas-passages, with the regulator-casing detachable from said frame, and having a valved opening, through which it communicates with the inlet-passage, and a laterally-projecting hollow neck fitted

to but removable from an opening in the discharge-passage, all substantially as specified. 30

2. The combination of the outer frame, having hollow arms forming gas-passages, with the regulator-casing seated upon said frame at one end, and having at the other end a conical 35 nut, the point of which bears upon the frame, all substantially as specified.

3. The combination of the outer frame, having arms forming gas-passages, the regulator-casing contained within said frame, and a hollow 40 plug passing through and communicating with the discharge-arm of the frame and adapted to a seat on the casing of the regulator, all substantially as specified.

4. The combination of the regulator-casing, 45 the diaphragm, and the valve carried thereby, with a transverse stem having beneath the valve an eccentric portion for restricting the drop of the valve, all substantially as specified.

In testimony whereof I have signed my name to this specification in the presence of two subscribing witnesses.

H. W. RAPPLEYE.
